DESIGN FOR A COMBINED FISHING REEL AND ROD HANDLE

Andrew A. Wacht, Detroit, Mich.

Application May 6, 1947, Serial No. 138,855

Term of patent 3½ years

(Cl. D31—4)

To all whom it may concern:

Be it known that I, Andrew A. Wacht, a citizen of the United States and resident of the city of Detroit, county of Wayne, and State of Michigan, have invented a new, original, and ornamental Design for a Combined Fishing Reel and Rod Handle, of which the following is a specification, reference being had to the accompanying drawings, forming part thereof.

Fig. 1 is a left side elevational view of a combined fishing reel and rod handle, showing my new design;

Fig. 2 is a top plan view of said combined fishing reel and rod handle.

Fig. 3 is a right side elevational view of said combined fishing reel and rod handle.

The essential feature of my design resides in the reel portion.

I claim:

The ornamental design for a combined fishing reel and rod handle, as shown and described.

ANDREW A. WACHT.
